UNITED STATES PATENT OFFICE.

ALMER M. McAFFEE, OF PORT ARTHUR, TEXAS, ASSIGNOR TO GULF REFINING COMPANY, OF PITTSBURGH, PENNSYLVANIA, A CORPORATION OF TEXAS.

IMPROVING OILS.

1,326,072.

Specification of Letters Patent. Patented Dec. 23, 1919.

No Drawing.

Application filed June 26, 1918. Serial No. 242,077.

To all whom it may concern:

Be it known that I, ALMER M. McAFFEE, a citizen of the United States, residing at Port Arthur, in the county of Jefferson and State 5 of Texas, have invented certain new and useful Improvements in Improving Oils, of which the following is a specification.

This invention relates to improving oils; and it comprises a method of improving the 10 quality of the more volatile petroleum oils, such as gasolene and burning oils, wherein such oils are boiled with aluminum chlorid, or a like material, with partial refluxing of vapors and control of the temperature of the 15 vapors passing the refluxing, such vapors so passing being then condensed; as for instance in converting unsaturated crude cracked gasolene containing large amounts of high boiling material into a substantially 20 homogeneous saturated product of a less range of boiling points and particularly adapted for aeroplane work wherein such crude gasolene is boiled with a few per cent. of aluminum chlorid, vapors of high boiling 25 bodies refluxed and vapors permitted to leave the system at, say, 200 to 250° F. and then condensed; all as more fully hereinafter set forth and as claimed.

As I have discovered and elsewhere de- 30 scribed and claimed (Serial No. 792,615) high boiling oils can be converted into gaso- 35 lene or into gasolene and burning oil by boiling with aluminum chlorid under partial reflux means, the reflux means being adapted to condense and return everything condensable at 350° or 300° F., and vapors having a 40 temperature not higher than that indicated being sent to a suitable condenser. If the temperature of the vapors at the time of 45 access to the condensing line be not above about 300 F., all the condensed product will be merchantable gasolene. Whatever the character of the original oil, the condensate will be of saturated character, not needing 50 the usual sulfuric acid treatment to remove unsaturated bodies. If the temperature of the vapors at the time of exit to the condenser be around 350° F., the condensate will be a material which can be fractionated 55 into gasolene and burning oils. This condensate, like the former is of saturated character. In another application (Serial No. 1375, January 9, 1915) whereof the present is a continuation of so much as is common 60 to the two, I have described this principle as

applied to the improvement of vapors of various commercial low boiling oils, such as gasolene and I do not claim herein such vapor treatment.

Gasolene as it comes on the market is 60 partly of the type known as refinery gaso- 65 lene, that is volatile oils naturally contained in crude petroleum and obtained therefrom by a simple distillation operation. In part, commercial gasolene is obtained by destruc- 70 tive distillation of higher boiling oils; by what is known as cracking. In cracking the oil is heated above 600° F. and undergoes a breaking down with the result of pro- 75 ducing low boiling oils of the character of gasolene. Sometimes cracking is under pres- 80 sure to maintain the oil liquid at a higher temperature than would otherwise be possible; and sometimes cracking is done with the ordinary pressure. Whatever the way of cracking adopted, the product is not of as 85 good character as refinery gasolene, being usually "unsaturated" in its character. Gaso- 90 lene as marketed, whether cracked gasolene or refinery gasolene, is a non-homogeneous material, with a wide range of boiling point, a difference of many degrees between its initial and end boiling points. It con- 95 tains a proportion of very low boiling oils and usually a large proportion of relatively high boiling oils. While the commercial 100 gasolene of course varies, much of it begins to boil at 120° F. and it is not all distilled below 350° F. This is immaterial for most of the uses of gasolene, but for some types of engine, and particularly those employed in aeroplanes, a more homogeneous material is desired.

In the present invention it is one of my objects to convert commercial gasolene into 95 a material of higher quality, both as regards homogeneity and in other respects. The material made by the present process, whether made from refinery gasolene or cracked gasolene, may be produced of homo- 100 geneous character, with any desired narrow range of boiling point; and it will be of completely saturated character, having an agreeable odor and needing no refining.

In the acknowledged prior application 105 (Serial No. 792,615) high boiling oils, such as gas oil, are boiled with aluminum chlorid at whatever temperature the boiling mixture will assume. With a gas oil which alone would begin to boil at, or above say, 110

600° F., the mixture with about 5 per cent. of aluminum chlorid enters into ebullition with sufficient evolution of vapors for distillation at about 500° to 550° F., the particular temperature depending partly on the oil and partly on the proportion of the aluminum chlorid—and the degree of activity of the chlorid.

Two different results may be secured by 10 the use of aluminum chlorid on gasolene: the homogenizing effect in converting material of a wide range of boiling points into material of a narrower range; and the saturating effect in converting unsaturated hydrocarbons into saturated. Both are desirable in improving cracked gasolenes. If the gasolene be boiled with aluminum chlorid under partial refluxing and escape of vapors at a definite temperature, say, 150° F. 15 or 250° F. as the case may be, the higher boiling portions are converted into lower boiling and the condensate as a whole may be of any desired narrow boiling range. It will also be of saturated character whatever 20 that of the original gasolene. The saturating effect alone may be obtained by simply warming the gasolene with aluminum chlorid at, say, 120° F. to 150°, stirring vigorously. Some portion of the gasolene being volatile at these temperatures, in 25 this operation a reflux condenser is used to prevent escape of vapors from the system and return them to the action of the chlorid. On cooling and allowing the gasolene 30 to become quiescent, most of the aluminum chlorid will deposit out as a heavy sludge which may be easily removed. Cooling may be whenever the desired degree of saturation (as indicated by the iodin test) is attained. The gasolene may be freed of any 35 residual suspended or dissolved aluminum chlorid by redistillation or by treatment with a little sulfuric acid. The aluminum chlorid sludge may be used for a preliminary 40 treatment of another charge in order to exhaust its activity, the treatment of this second charge being then continued with fresh chlorid. The gasolene obtained in operating at these low temperatures will be, 45 in boiling point and distilling characteristics, much like the original but it will differ therefrom in that it requires no treatment with sulfuric acid to remove unsaturated compounds.

50 By a modification of the described method I may also materially improve the quality of these cracked gasolenes in other respects than the conversion of the unsaturated into the saturated hydrocarbons.

55 There is a demand for gasolene distilling within a narrower temperature range than that of ordinary gasolene which, as it now occurs on the market, may begin to distil at 120° F. and end at a distilling temperature 60 of 350° F. In so doing I take advantage

not only of the property of aluminum chlorid of converting unsaturated into saturated bodies, but also of its property of converting higher boiling oils into lower boiling. For this purpose I operate at a somewhat 70 higher temperature in treating the mixture of gasolene and aluminum chlorid than that just described. This higher temperature produces more or less distillation and I control this distillation in a special way. 75 This treatment may not only be applied to the commercial "cracked gasolenes" but also to the cracked distillates from which these cracked gasolenes are made by redistillation. These cracked distillates begin to boil 80 at about 120° F. and have a final boiling point of about 500° F., or possibly above. To this end I mix the material with aluminum chlorid as before and heat to the boiling temperature of the mixture under such conditions as will permit a refluxing of vapors of high boiling, or heavy, portions or fractions. The vapors may be allowed to pass to the final condensing system at a temperature between 150° F. and 250° F. A temperature of 200° F. is sometimes used. The product here is, as before, a clean sweet gasolene but it is of more uniform characteristics than the original, having a closer distillation range. 90

95 In a specific embodiment of the present invention any commercial grade of gasolene is charged together with some anhydrous aluminum chlorid into a suitable still provided with stirring means. As a rule about 100 5 per cent. of fresh aluminum chlorid is a desirable proportion. Aluminum chlorid which has been used in other methods of treating oil until its activity is partially exhausted may be employed here; but in 105 this event the proportion employed is concomitantly larger. The still should be provided with reflux means and the operation so conducted that the vapors passing the reflux means emerge, say, 150° to 250° F. 110 By conducting the firing or heating to give vigorous ebullition of the mixture of gasolene and aluminum chlorid, a chemical action takes place and the gasolene will be converted into a highly volatile product of 115 uniform nature and completely saturated character. All, or substantially all, of the gasolene will be converted into this homogeneous product. If the temperature of the vapors at the point of exit be held at about 120 200° F. all the product will be of this character. If the temperature be held somewhat higher, say 250° F., the distillate may need rectification. In this event residues from the rectification may be re-submitted to the 125 process or sold as burning oil of high quality.

130 A similar operation may be performed on kerosene or burning oil of low grade with the production of high grade kero-

sene of substantially uniform character. In so treating kerosene there is generally the production of more or less gasolene which is separated from the distillate by 5 suitable distillation.

The gasolene used should be dry and as free from sulfur as possible. Both moisture and sulfur tend to exhaust the activity of the aluminum chlorid uselessly. The operation 10 may be performed in apparatus of any of the common materials, such as iron and steel. The aluminum chlorid used should be anhydrous, the hydrated aluminum chlorid not being effective for the present purposes. 15

This application is a continuation in part of my copending application Serial No. 1375, filed January 9, 1915.

What I claim is:

- 20 1. In the manufacture of high grade gasolene, the process which comprises subjecting cracked gasolene at a temperature below its end boiling point to the action of aluminum chlorid in sufficient amount to convert unsaturated compounds into low boiling saturated compounds.
- 25 2. In the manufacture of high grade gasolene, the process which comprises boiling cracked gasolene with aluminum chlorid in sufficient amounts to convert unsaturated compounds into low boiling saturated compounds.
- 30

3. The process of converting higher boiling oils into lower boiling oils of high grade which comprises cracking such higher 35 boiling oils to form lower boiling products, condensing said product and thereafter exposing such lower boiling products to the action of aluminum chlorid.

4. The process of improving the quality 40 of gasolene and homogenizing it which comprises boiling with aluminum chlorid a gasolene having a wide range of boiling points, refluxing the more condensable vapors arising from such boiling operation while condensing vapors of lower boiling point and continuing the operation until the gasolene is distilled over as a gasolene of a narrower range of boiling points.

5. The process of homogenizing gasolene 50 which comprises boiling with aluminum chlorid a commercial gasolene having constituents higher boiling than 250° F., cooling the vapors to a temperature not above 250° F. and returning the condensate for 55 renewed action by aluminum chlorid, condensing vapors passing over at a temperature below 250° F. and continuing the operation until substantially all of the original gasolene is converted into a distillate free 60 of the higher boiling constituents.

In testimony whereof, I affix my signature hereto.

ALMER M. McAFFEE.
